W. Manning,
Mower.

No. 9138

Patented July 20, 1852

UNITED STATES PATENT OFFICE.

WILLIAM MANNING, OF SOUTH TRENTON, NEW JERSEY.

IMPROVEMENT IN GRASS-HARVESTERS.

Specification forming part of Letters Patent No. 9,138, dated July 20, 1852.

To all whom it may concern:

Be it known that I, WILLIAM MANNING, of South Trenton, in the county of Mercer and State of New Jersey, have invented certain new and useful Improvements in Mowing and Grass-Cutting Machines; and I do hereby declare that the following is a full, clear, and exact description thereof, reference being had to the accompanying drawings and letters marked thereon, forming a part of this specification.

Figure 1 represents a top or plan view; Fig. 2, a side elevation, and Fig. 3 the cutting-head with the top removed.

In each of these figures, where like parts are shown they are designated by the same letters of reference.

My invention relates to certain improvements in mowing or grass-cutting machines.

In the accompanying drawings, Figure 1 is a plan or top view; Fig. 2, a side elevation, and Fig. 3 the cutting-head with the top removed.

The same letters refer to like parts in each of these figures.

The manner of collecting and discharging the cut grain consists in the use and adaptation of an endless band or apron, g' , provided with teeth or fingers h , rotating on two vertical rollers, $i i$, immediately above and over the knives or cutters, but independent of them. The rollers have their lower bearings in each end of the top plate of the cutting-head, and their upper bearings in a metal rod, q , extending the width of cutting-head, and said rod is steadied and braced by braces $w w$, which serve the double purpose of keeping the rollers vertical, and by their flexibility allow the cutting-head to be raised or lowered by the lever s and rods $u u$ when it is desired to alter the angle of the cutters with the ground.

$a a$ are the driving-wheels, which are attached to the main axle, which is in the rear end of the machine. These wheels have cogs cut on their peripheries a few inches below or inside of their outer circumferences. Meshing into these cogs are two small pinions, $c c$, firmly attached to the shafts of the double-grooved pulley-wheels $b' b'$, which shafts have

their bearings in the frame-timbers $x x'$, and around said grooved wheels are two sets of cords, $b d$, passing from thence over pulleys $p p$, under pulleys $h' h'$, and around the pulleys 1 of the knives or cutters, the pulleys 4 on the bottom of the cutting-head, and around pulleys $g g$ on the rollers $i i$. Thus the desired rotary motion is given to the knives and endless apron from the main driving-wheels.

To keep a proper tension on the cords b and d , I provide movable boxes for the pulleys $p p$, so that by the action of weights $t t$ the pulleys press against said cords and keep them constantly taut. This plan of gearing the knives or cutters and endless band with the driving-wheels I have found to be the best.

The manner of sustaining the cutting-head and front part of the machine without the aid of front wheels consists in constructing the frame-timbers $x x'$ very light, but of strong material, and bracing them to the axle with metal rods $x^2 x^2$, and jointing the tongue l , to the end of which the neck-yoke is attached, in the center of the main shaft or axle, and swinging the neck-yoke m , by chains, from the hames of the harness, and the cutting-head from the neck-yoke, also by chains $o o$, which chains can be taken up or let out, so as to raise or lower the cutting-head, according to the description of grain to be cut.

The cutting-head is suspended on pivots in the metal pieces $5 5$ on the end of the side timbers $x x'$, and rising from the top of the cutting-head at each end are arms $r r$, jointed to which are rods $u u$, extending to the rear end of the machine, and there the rods $u u$ are jointed to a bar and lever, s , the lever s having its fulcrum on the main axle. This lever s is convenient to the operator or farmer, by which he can raise or depress the cutting-head on its pivots, so as to regulate the angle of the cutters with the ground as desired, and thus pass over stumps, stones, or other obstructions which may be upon the surface of the ground.

The advantages of this machine over many others I conceive to be numerous. Among the most important may be mentioned its lightness, consequently requiring but little power to

drive it, and its efficient action, and being suspended from the shoulders of the animals propelling it, it is easily guided and governed.

Having thus fully described my invention, what I claim as new, and desire to secure by Letters Patent, is—

Suspending the cutting-head and front part of the machine, whereby I dispense with front

wheels, by constructing the frame as described, and attaching the cutting-head to the bames of the harness, in the manner and for the purpose herein fully set forth.

WILLIAM MANNING.
